United States Patent Office

Des. 191,682
Patented Oct. 31, 1961

191,682

THERMOMETER

Ralph C. Wappner, Springfield, Ohio, assignor to The Ohio Thermometer Co., Springfield, Ohio, a corporation of Ohio

Filed Aug. 8, 1960, Ser. No. 61,654

Term of patent 14 years

(Cl. D52—7)

FIG. 1 is a perspective view of a thermometer, on a reduced scale, showing my new design;

FIG. 2 is a side view thereof;

FIG. 3 is a top view thereof;

FIG. 4 is a bottom view thereof; and

FIG. 5 is a back view thereof.

The essential features of my design reside in the portion shown in full lines.

I claim:

The ornamental design for a thermometer, substantially as shown and described.
